UNITED STATES PATENT OFFICE

EMMA C. WOOSTER, OF NEW YORK, N. Y., ASSIGNOR TO JAMES V.
ROCKWELL, OF SAME PLACE.

DESIGN FOR RUCHES.

Specification forming part of Design No. 7,231, dated March 3, 1874; application filed January 31, 1874.
[Term of Patent 3½ years.]

CASE A.

To all whom it may concern:

Be it known that I, EMMA C. WOOSTER, of the city, county, and State of New York, have invented a Design for Ruches, of which the following is a specification:

The nature of my design is fully represented in the accompanying drawing, to which reference is made.

Figure 1 is a view, in perspective, of a ruche made in accordance with my new design; Fig. 2, a transverse profile of the same; and Fig. 3, 2, an edge view or profile of the inner ruffle.

Similar letters of reference indicate corresponding parts.

A represents the exterior, and B the interior, portions or borders of the ruche, both formed of ruffles or flutings, the transverse sections of which are of mainly circular or

loop-like profile, as shown in Fig. 2, with rolling or rounded outer edges terminating at their backs and inner edges in flattened or straight continuations, said round-edged and loop-like flutings lying back to back. Within these two ruffles or flutings A B is a longitudinally-waved ruffle or fluting, C, the flutes of which spread outwardly, and are contracted or flattened at their inner edges, where said fluting joins the back of the interior border-fluting B.

What I claim as my invention is—

The design for ruches, substantially as herein described and shown.

EMMA C. WOOSTER.
